UNITED STATES PATENT OFFICE.

HENRY H. THORP, OF CLEVELAND, OHIO, ASSIGNOR TO THE H. H. THORP
MANUFACTURING COMPANY, OF SAME PLACE.

DESIGN FOR PRINTING-TYPES.

SPECIFICATION forming part of Design No. 12,815, dated March 14, 1882.

Application filed January 18, 1882. Term of patent 14 years.

To all whom it may concern:

Be it known that I, HENRY H. THORP, of the city of Cleveland, in the county of Cuyahoga and State of Ohio, have produced a new and original Design for Printing-Types, of which the accompanying specimen or impression is an exact representation, and is made a part of this specification.

The design may be used either with or without the shading shown, and by my claim I desire to cover both forms.

I claim—

The design for printing-types herein shown and described.

HENRY H. THORP.
